UNITED STATES PATENT OFFICE.

CARL W. DEHN, OF TOPEKA, KANSAS.

GAS AND GASOLENE ENGINE.

1,095,196.

Specification of Letters Patent.

Patented May 5, 1914.

Application filed May 16, 1913. Serial No. 767,961

To all whom it may concern:

Be it known that I, CARL W. DEHN, a citizen of the United States, residing at Topeka, in the county of Shawnee and State of Kansas, have invented certain new and useful Improvements in Gas and Gasolene Engines, of which the following is a specification.

The object of my invention is to improve generally upon gas and gasolene engines of the two-cycle type, with special regard to economy of construction, simplicity of design, reduction of the number of working parts, accessibility to all parts, strength, durability, compactness, and permanence of adjustment.

My invention comprises a cylinder having two oppose piston chambers, a piston in each chamber, and cross-head bars connecting the two pistons and having sliding bearings against the walls of the cylinder.

It also comprises such parts with the guides for the cross-head bars, integral with the cylinder walls, a straight shaft mounted on one of the cylinder heads and carrying fly-wheels to which motion is communicated by means of connecting rods extending between them and the cross-head bars respectively.

It also comprises the parts, improvements, and combinations hereinafter set forth and claimed.

In the drawings accompanying and forming part of this specification and in the description of the drawings I have shown my invention in its preferred form and what I deem to be the best mode of applying the principles thereof; but it is to be understood that, within the scope of the appended claims, I contemplate changes in form, proportions, and materials, the transposition of parts, and the substitution of equivalent members, without departing from the spirit of my invention.

Figure I is a sectional plan view of an engine made in accordance with the principles of my invention. Fig. II is a central vertical sectional elevation. Fig. III is a side elevation. Fig. IV is a transverse sectional view of one of the piston chambers on a plane indicated by the line 4—4 in Fig. II. Fig. V is a transverse section of the engine, the right-hand half being on a plane indicated by the line 6—6, and the left-hand half being on a plane indicated by the line 5—5, in Fig. II.

Similar reference characters indicate like or corresponding parts throughout the several views.

The cylinder A is formed with two piston chambers B, B, one at each end and opposed to each other, and a central transverse imperforate partition C. The cylinder walls are surrounded by two water jackets D, D, each extending from the end to about one-half the distance to the center of the cylinder. A water-jacketed cylinder head is provided at each end, as indicated at E and F, respectively, the latter having bearing blocks G, G either integral therewith or rigidly secured thereto, and preferably spaced apart from each other, and forming bearings for the straight shaft H.

Working in the respective piston chambers are the opposed pistons I, I. The spaces between the pistons and the middle partition serve as initial compression chambers, and the spaces on the opposite sides of the pistons as combustion chambers. The arrangement of the admission ports J, J, the exhaust ports K, K, and the by-passes L, L is that commonly found in other types of two-cycle engines, there being a separate complete set for each half of the cylinder. Through the inner end of each piston extends a hollow pin M whose ends extend through slots N, N in the cylinder walls, the slots being of sufficient length to allow for the stroke of the engine. Cross-head bars O, O are located on diametrically opposite sides of the cylinder and have working, or slide, bearings against the walls and between guides P, P, formed integral with the cylinder. Each cross-head bar is secured to the similarly extended ends of the respective pins, and extends therebetween forming a closure for the adjacent slots. In order to secure a perfect closure, I provide compression springs Q, Q bearing between the cross-head bars and the nuts R, R secured to opposite ends respectively of bolts S, S extending through the hollow pins. A packing T is arranged, where the pin extends through the slot, to completely fill the space between the piston and the cross-head bar and between the opposed sides of the slot.

A wrist-pin U is secured to the middle of each cross-head bar. The shaft carries two fly-wheels V, V, each having a crank-pin W, and the respective wrist- and crank-pins are connected by connecting rods X, X, respectively. Disks or arms Y, Y may be secured

to the respective crank-pins, providing a means for attaching driving mechanism for auxiliaries, such as pump, magneto, etc.

5 The space between the shaft bearings may be used for mounting on the shaft any suitable transmission device, such as a sprocket-wheel, or other suitable device.

10 The two pistons act in unison by being secured together through the medium of the cross-head bar. The power or forward stroke of the one piston causes the initial compression in the compression chamber of that part of the cylinder in which that piston works, and also causes the return stroke 15 of the opposed piston, which in turn compresses the gas in the combustion chamber and draws the new gas into the combustion chamber.

20 It will be noted that the compression chambers are relatively small when compared with the ordinary crank-case compression chamber, thus insuring a more complete scavenging of the combustion chamber and a higher compression in the combustion chamber. It will also be noted that at 25 the end of the forward stroke of each piston, the side slots in the chamber for that piston are practically closed by the walls of the hollow piston, and that as the pressure increases in the compression chamber, the area 30 of the cross-head bars exposed to such pressure decreases; hence it is obviously not necessary that the springs be so highly tensioned as to cause undue friction. It will be 35 also noted that while my engine as a whole is compact and short, my design permits the use of relatively long connecting rods, thus reducing the angular side thrust, making a more direct, easier running, and more 40 powerful engine. The force of each explosion is equally divided on the two connecting rods, which makes a well balanced stroke. Also it makes possible the proportioning of parts so that wear of pins and 45 bearings is reduced without any increase of weight per cylinder. The arrangement of the cross-head bars relieves the pistons of side-thrust which would otherwise wear the cylinder out of round. Further advantages 50 are: There are few parts and they are all easily and cheaply manufactured. There is little liability of any of the parts getting out of order while in service, and no adjustments to be made after the engine is once 55 assembled. All working parts are readily accessible, and can be easily removed and replaced. The various duplicated parts may be interchangeable so that any part may be used in either of the two places, as the cross-head bars, the connecting rods, the pistons. 60 Also the cylinder heads may be interchangeable so as to place the shaft at either end.

What I claim is:

65 1. In a two-cycle engine, the combination of a casing having two opposed piston cham-

bers, having a centrally disposed transverse imperforate partition between the two chambers, having suitable admission and exhaust ports and by-passes, having shaft bearings at one of its ends, having longitudinally extending and diametrically opposite slots through the side walls of each chamber, and having longitudinally extending guides adjacent to each slot; a piston in each chamber; a pin secured to each piston, the ends of each pin extending through opposite slots respectively; a cross-head bar on each side of the casing, each bar being secured to the similarly projecting pin ends and covering the slots between said pin ends and having a sliding bearing against the wall of the casing and between adjacent guides; said pins and cross-head bars forming rigid connections between the two pistons and said cross-head bars forming sliding closures for the respectively adjacent slots; a shaft mounted in said end bearings; a fly-wheel mounted on each end of the shaft; and two connecting rods directly connecting the cross-head bars with the fly-wheels respectively.

2. In a two-cycle engine, the combination of a casing having two opposed piston chambers, having a centrally disposed transverse partition between said two chambers, having suitable admission and exhaust ports and by-passes, having shaft bearings at one of its ends, and having longitudinally extending and diametrically opposite slots through the side walls of each chamber; a piston in each chamber; a pin secured to each piston, the ends of each pin extending through opposite slots respectively; two cross-head bars, one on each side of the casing, each bar being secured to the similarly projecting pins of the two pistons, and each bar having a sliding bearing against the outside of the adjacent casing wall and forming a closure for the adjacent slots between the pistons; a transverse shaft mounted in said end bearings; two fly-wheels, one mounted on each end of said shaft; and two connecting rods directly connecting the cross-head bars and fly-wheels respectively.

3. In a two-cycle engine, the combination of a casing having two opposed piston chambers, having a centrally disposed transverse partition between said two chambers, having suitable admission and exhaust ports and by-passes, and having longitudinally extending and diametrically opposite slots through the side walls of each chamber; a piston in each chamber; a pin secured to each piston and extending through the opposite slots; and a cross-head bar on each side of the casing, each bar being connected with the similarly projecting pins of the respective pistons, having a sliding bearing against the casing, and forming a closure for the adjacent slots.

4. In a two-cycle engine, the combination

of a casing having two opposed piston chambers, having a centrally disposed transverse partition between the two chambers, having suitable admission and exhaust ports and 5 by-passes, and having longitudinally extending and diametrically opposed slots through the side walls of each chamber; a piston in each chamber; a pin secured to each piston and projecting through opposite slots; a 10 cross-head bar on each side of the casing, having sliding bearing against the same, connecting similarly projecting pins, and forming a sliding closure for the adjacent slots; and a spring at each pin-and-cross- 15 head-bar connection bearing between the pin and the cross-head bar and forcing the cross-head bar against its sliding bearing.

5. In a two-cycle engine, the combination of a casing having two opposed piston chambers, having a centrally disposed transverse partition between the chambers, having suitable admission and exhaust ports and by-passes, and having longitudinally extending and diametrically opposed slots through 20 the side walls of each chamber; a piston in each chamber; two cross-head bars on opposite sides respectively of the casing, said bars forming closures for the respective slots, and having sliding bearings against said 25 casing; and means extending through the respective slots connecting said pistons with said cross-heads.

30 6. In a two-cycle engine, the combination of a piston cylinder having longitudinally ex-

tending diametrically opposed slots through 35 its side walls; a piston in said cylinder; a cross-head bar on each side of the cylinder; means extending through said slots and connecting the piston with the respective cross-head bars; said bars forming sliding closures 40 for the respective slots, and springs for pressing said bars against their respective sliding bearings.

7. In a two-cycle engine, the combination of a casing having two opposed piston chambers, having a centrally disposed transverse partition between the two chambers, having admission and exhaust ports and by-passes, and having longitudinally extending and diametrically opposed slots through the side 45 walls of each chamber; a piston in each cylinder; a cross-head bar on each side of the casing, said cross-head bars forming closures for the respective slots and having sliding bearing against said casing; pins extending 50 through the respective slots and connecting the bars with the pistons; a straight shaft mounted at one end of the casing; a fly-wheel mounted on each end of the shaft, one fly-wheel on each side of the casing; and 55 connecting rods directly connecting the bars with the fly-wheels respectively.

In testimony whereof I have affixed my signature in presence of two witnesses.

CARL W. DEHN.
